UNITED STATES PATENT OFFICE.

MICHEL MELLER-ZAKOMELSKY, OF NEW YORK, N. Y.

ENGINE-STARTER.

1,101,465.

Specification of Letters Patent. Patented June 23, 1914.

Application filed November 18, 1913. Serial No. 801,647.

To all whom it may concern:

Be it known that I, MICHEL MELLER-ZAKOMELSKY, a subject of the Czar of Russia, and a resident of the city of New York, 5 Elmhurst, borough of Queens, in the county of Queens and State of New York, have invented a new and Improved Engine- Starter, of which the following is a full, clear, and exact description.

This invention has special reference to an improved starter for internal combustion engines and more particularly to a device which is adapted for use in connection with automobiles.

The essential object of the invention is evolved in the provision of a starter which will permit the starting of the engine to secure initial compression and explosion from the chauffeur's seat, thus obviating the necessity of getting out of the car and turning the engine over by means of the usual crank, as well as permitting instant control of the throttle levers to regulate the speed of the engine or motor.

With the above and other objects in view, the invention consists of certain novel combinations with arrangements of parts as will be hereinafter more fully described, claimed and illustrated in the accompanying drawings, in which—

Figure 1 is a side elevation of a fragmentary portion of an automobile, with one side thereof broken away to disclose the improved starter; Fig. 2 is a plan view of the structure shown in Fig. 1, the foot board being broken away to disclose the starter and a portion of the latter being indicated in section; Fig. 3 is an enlarged side elevation of the starter, with a portion thereof in section; Fig. 4 is a sectional view taken on the line 4—4 of Fig. 3; Fig. 5 is a sectional view taken on the line 5—5 of Fig. 3; Fig. 6 is a sectional view taken on the line 6—6 of Fig. 3, with the lever in the shifted 45 position; Fig. 7 is a plan view of the starter with the operating lever in section; and Fig. 8 is a rear elevation of the device shown in Fig. 7.

In illustrating the preferred embodiment 50 and application of the invention, a fragmentary portion 10 of an automobile is shown, having the usual hood 11, housing the engine or motor 12, the drive shaft of which is provided with the usual fly wheel 13. In the present instance, the car is shown as having a closed body, from the

chauffeur's seat of which the usual steering wheel 14 is conveniently operable for steering the vehicle. At the present time, it is general to alight from the car and to start 60 the motor or turn over the same by means of a crank at the front of the hood and this requires a great deal of time, as well as distracting the operator's attention from the throttle levers controlling the running of 65 the engine so that the engine might unduly speed up. In the present device, I obviate these objections by permitting the engine to be started from the chauffeur's seat without alighting from the car and permitting 70 the chauffeur's attention to the control of the engine or motor, whereby it may be prevented from unduly speeding. For this purpose the fly wheel 13 has a beveled gear wheel 15 attached thereto at the rear edge, 75 while supported by means of a depending bracket 16, carried transversely beneath the foot board 17 of the car, is a shaft 18, the same being journaled in the grooves 19 of inclined bearings 20, supported upon up- 80 rights 21, the latter being preferably removably mounted on the bracket 16. The bearings 20, the grooves 19 of which communicate with the inner sides thereof, are provided with depending barrels or cylindrical portions 22, which are preferably threaded into the bearings as shown in Fig. 4 of the drawings. The ends of the shaft 18 rest upon bearing blocks 23 having depending stems 24, around which coiled 85 springs 25 are disposed within the barrels, the said springs tending to normally elevate the said blocks and shaft therewith to the top of the grooves in the bearings. Fixed to the shaft 18 is a segmental rack or bevelled gear 26, which is adapted to move into or out of engagement, or in mesh with the beveled gear 15, as will be hereinafter described.

Supported upon one of the bearings 20 100 is a segmental guide plate 27, the same being spaced from the bearing and stationed by means of side supports 28. This guide plate tapers from its rear to its forward end and in its inner face, is provided with 105 upper and lower grooves 29 and 30 located on arcs concentric to the shaft 18 when in raised or lowered positions respectively, in the grooves of the bearings. These grooves provide an intermediate or dividing 110 wall 31, which also tapers toward the forward end of the plate, while communicating

passages 32 and 33 are provided at the ends of the grooves 29 and 30. Carried by the end walls of the groove plate and projecting into the area of the communicating grooves 32 and 33, are beveled stops or bolts 34 and 35, the same being movable in openings 36 in said walls. These openings are closed by plugs 37, between which and the stops, springs 38 are mounted, said springs preferably being of V form and designed to exert pressure against the stops for forcing the same into the area of communicating grooves 32 and 33 respectively. The stop 34 is beveled upwardly and the stop 35 is beveled downwardly, whereby a lever 39, which is fixed to the shaft 18 adjacent to the segmental guide plate as regards its horizontal disposition, through the instrumentality of a lateral projecting detent 40, which engages the grooves, may be guided backward and forward in the plate during the upward and downward movement of the shaft in starting the motor and in permitting the motor with the beveled gear 15, to rotate independent of the segmental gear 26.

In the operation of the device, we will consider that the motor is at rest and that it is desired to start the same. For this purpose lever 39 which has a grasping portion 30 at its upper end, will be disposed in a forward position as shown in Fig. 1 and in solid lines in Fig. 3, so that the segmental beveled gear 26 will be in mesh with the beveled gear 15. This is due to the fact 35 that the shaft 18 is at the bottom of the grooves in the bearings 20, which are inclined toward the fly wheel and beveled gear carried thereby, thus shifting the segmental rack or gear 26 forwardly in mesh with the beveled gear 15 when the detent 40 is at one corner of the relatively rectangular continuous groove in the plate, or at the corner produced by the intersection of the grooves 30 and 33 respectively. In this position, the 40 stop 35 will prevent the lever from rising by pressure of the springs 25 against the shaft and by exerting a quick rearward pull upon the lever, the latter will ride rearwardly with the detent moving through the groove 30, so as to impart rotation to the fly 45 wheel and engine shaft for the purpose of causing an inward compression and explosion for starting the same. At the instant that the lever 39 reaches the near end of the groove 30, the springs 25 will operate to raise the shaft and shift the segmental gear 26 rearwardly and upwardly out of mesh with the gear 15, the detent engaging the beveled wall of the stop 34, so as to depress the latter against the action of the 50 springs 38, so that the detent will pass into the upper groove. When the shaft 18 is disposed at the lower ends of the bearings 20, the groove 30 which is concentric to the 55 shaft at such point, will permit the detent

40 to pass freely therethrough, while when the detent 40 is engaged in the upper groove 29, the shaft will have moved to the upper part of the bearings, in which position the groove 29 is concentric to the center of the shaft, the centers thus changing as the lever is shifted. The lever remains in this position after the engine is started and to again start the engine when necessary, the lever is thrust forward to cause the detent 40 to travel in the groove 29 while the segmental gear 26 is still out of mesh with the gear 15, but by lowering or pushing down on the lever, the detent 40 will engage the beveled wall of the stop 35, to depress the latter 80 against the action of the spring 38, the detent passing into the lower groove through the communicating groove 33 and being held from upper displacement by the stop. The gears are now in mesh and by pulling rearwardly on the lever in the manner hereinbefore described, rotation may be again imparted to the motor shaft. The segmental guide plate 27, as shown in Fig. 1, is projecting through a hood in the foot board, 85 but it is obvious that it may be disposed in any other relative position, the essential feature being the operation of the starting mechanism from the chauffeur's seat and by the specific means enumerated. 90

Having thus described my invention, I claim as new and desire to secure by Letters Patent:

1. In an engine starter, a combination with an engine shaft and fly wheel thereof; 100 of a gear fixed to the fly wheel, a depending bracket adapted to be supported from the chassis of an automobile, uprights having inclined grooved bearings, a shaft journaled in said bearings and movable in the grooves, 105 a segmental gear fixed to the shaft extending in juxtaposition to the first-mentioned gear, a segmental guide plate carried by one of the bearings and having a continuous groove, provided with upper portions located on arcs concentric to the shaft when in raised and lowered positions, a lever fixed to the shaft and having a detent operating in the groove, said shaft when lowered causing the engagement of the gears, whereby a 110 pull upon the lever will impart rotation to the engine shaft, and means acting upon the shaft to normally raise the latter in the bearings to disengage the gears. 115

2. In an engine starter, a combination with an engine shaft and fly wheel thereof; 120 of a gear fixed to the fly wheel, a depending bracket adapted to be supported from the chassis of an automobile, uprights having inclined grooved bearings, a shaft journaled in said bearings and movable in the grooves, 125 a segmental gear fixed to the shaft extending in juxtaposition to the first-mentioned gear, a segmental guide plate carried by one of the bearings and having a continuous 130

- groove, provided with upper portions located on arcs concentric to the shaft when in raised and lowered positions, a lever fixed to the shaft and having a detent operating 5 in the groove, said shaft when lowered causing the engagement of the gears, whereby a pull upon the lever will impart rotation to the engine shaft, stops at the ends of the grooves designed to permit the detent to 10 pass downwardly at the forward end of the plate and upwardly at the rear end of the plate, but to prevent opposite movement thereof in the groove, barrels carried by the bearings, and springs in the ballers acting 15 on the ends of the shaft journaled therein for normally elevating the latter, to cause the detent to pass from the lower portion to the upper portion of the groove to disengage the gears at the end of the operative stroke. 20 3. The combination with an engine shaft of bearings supported adjacent thereto, a shaft movable in the bearings, drive connections between the engine shaft and the second-mentioned shaft adapted upon move- 25 ment of the second-mentioned shaft in the bearings to be engaged and disengaged, means for normally elevating the second-named shaft in the bearings, a lever connected to the second-named shaft, and a guide 30 engaged by the lever to permit movement of the shaft by means thereof when the shaft is in raised or lowered position. 35 4. An engine starter comprising the combination with the crank shaft of an internal combustion motor; of a shaft adapted to be
- geared to the crank shaft, means supporting the shaft for movement to permit the same to move into and out of operative position, a lever fixed to the shaft, a guide having a groove coöperating with a portion of the 40 lever and limiting forward and rearward movement thereof when in raised or lowered positions, and means communicating with the groove at the ends of the guide to permit the lever to be depressed at the forward limit 45 and to hold the lever against upward displacement, while permitting upward displacement of the lever at the rear end of the groove and preventing the downward displacement thereof. 50 5. The combination with a motor vehicle having an internal combustion motor and the crank shaft of the motor having a fly wheel; of a gear fixed to the fly wheel, a shaft, a segmental gear carried by the shaft 55 and coöperating with the first-mentioned gear, and means movably supporting the shaft for elevation in an inclined direction and permitting the same to be rotated for imparting rotation to the crank shaft 60 through the intermeshed gears and permitting disengagement of the gears at a pre-determined point.

In witness whereof I have signed my name to this specification in the presence of two 65 subscribing witnesses.

MICHEL MELLER-ZAKOMELSKY.
